[57] CLAIM

The ornamental design for a train clock, as shown and described.

DESCRIPTION

FIG. 1 is a perspective view showing the front, top and left sides of the train clock, embodying my new design; FIG. 2 is a front elevational view thereof, the dotted line depiction of clock numerals being for illustrative purposes only and forming no part of the claimed design;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

FIG. 1

FIG. 2

FIG. 3
